UNITED STATES PATENT OFFICE.

FRANK F. FORSHEE, OF FLINT, MICHIGAN, ASSIGNOR TO WESTINGHOUSE ELECTRIC PRODUCTS COMPANY, A CORPORATION OF MICHIGAN.

QUICK-ACTING KNIFE SWITCH.

Application filed November 20, 1919. Serial No. 389,266.

To all whom it may concern:

Be it known that I, FRANK F. FORSHEE, a citizen of the United States, and a resident of Flint, in the county of Genesee and 5 State of Michigan, have invented a new and useful Improvement in Quick-Acting Knife Switches, of which the following is a specification.

My invention relates to switches and 10 particularly to operating mechanisms therefor.

One object of my invention is to provide a quick-acting knife-blade switch that shall be simple and durable in construction, effective in operation and economical to manufacture.

Another object of my invention is to provide a quick-acting knife-blade switch having such construction that a relatively slight 15 movement of an actuating member will operate the switch.

Another object of my invention is to provide a device of the above indicated 20 character that shall have an automatically 25 shiftable fulcrum member for a toggle-lever operating mechanism.

Another object of my invention is to provide an improved lever and biasing mechanism for a knife-blade, or other relatively large, switch that shall occupy a 30 relatively small amount of space.

Heretofore, in adapting knife-blade switches for operation upon the time-actuating snap or quick-acting principle, it has 35 been necessary, in certain of these devices, to employ relatively cumbersome and extensive auxiliary means. This was due to the relatively great throw of the movable parts and the greater leverages which, 40 therefore, came into play.

In practicing my invention, I provide a knife-blade switch adapted for automatic actuation at predetermined time intervals in which the biasing or snap-actuating mechanism is of relatively compact construction 45 and in which the relatively great movement of the blade is effectively reduced in the actuating mechanism. This is accomplished by the novel relation of a spring and a 50 floating link to the switch.

Figure 1 of the accompanying drawings is a view, partially in section and partially in side elevation, of a switch embodying my invention and a time-actuating mecha-

nism therefor, and Fig. 2 is a view of the 55 switch taken at right angles to Fig. 1.

In general, my device comprises a double-pole, knife-blade switch 1 having the usual pivot-supporting jaw members 2 for the support of knife-blade members 3, jaw 60 members 4, an insulating base 5, a supporting plate or member 6 and a spring-and-lever or toggle mechanism 7. A usual transverse insulating bar or member 8, attached to the outer ends of the blade members 3, carries a handle 9 that is adapted, in an open position of the switch, to project into the path of a roller or other projection 10 at the end of a lever 11 that is attached to a winding stem 12 of an ordinary alarm 70 clock 13, or otherwise mounted, and actuated to engage the handle 9 at a predetermined time.

A rod or bar 14, rigidly disposed on the member 8 in substantially parallel relation 75 to the blade members 3 and projecting oppositely to the handle 9 to a point beyond the pivot-supporting jaw members 2, is pivoted at its outer end, by a pin 15, to one end of a floating link 16 that extends 80 through an opening 17 in the member 6.

The other end of the link 16 is attached to one end of a spring 18 that may be anchored, at its other end, by any suitable means, as by a bolt 19 and nuts 20 that may 85 also serve to secure the base member 5 to the member 6.

In moving the switch from the closed, or full-line, position to the open, or dotted-line, position, the blade members 90 3, by reason of their relation to the mechanism 7, pass through a neutral position, on either side of which the blade members 3 are biased, by the spring 18, towards their open or closed positions.

During the closing and opening operations, the link 16 slides along an edge 21 of the member 6 adjacent to the opening 17 and, thereby, automatically changes the fulcrum of the link. This feature of 100 105 changeable fulcrum for the mechanism 7, together with the novel arrangement of parts, permits the mechanism to be smaller and more compactly arranged and the handle 9 to be actuated by a relatively small amount of movement of the lever 11.

While I have shown and described a particular form of my invention, changes

may be effected therein without departing from the spirit and scope thereof, as set forth in the appended claims.

I claim as my invention:

- 5 1. A switch comprising a pivoted knife-blade member, a member extending transversely therefrom, a projecting member operatively connected to said transverse member and extending substantially parallel to 10 the blade member, to one side of the pivot point of the latter, resilient means for biasing the blade member, a floating link movably connected to said projecting member and to said means, and means engaging the 15 link intermediate its ends for directing the movement thereof.
2. A switch comprising a pivoted knife-blade member, a projecting member operatively connected to the blade member and 20 extending substantially parallel to the blade member, to a point at one side of the pivot point of the latter, resilient means for biasing the blade member, a floating link movably connected to said projecting member 25 and to said means, and means engaging the link intermediate its ends for directing the movement thereof.
3. A switch comprising a supporting member, a pivoted blade member supported 30 on one side thereof, resilient means for biasing the blade disposed on another side of the supporting member, a link for joining the blade to said means, said supporting member engaging the link intermediate 35 its ends for directing the movement thereof.
4. A switch comprising a supporting member having an opening therein, a pivoted blade member supported on one side of the supporting member, resilient means 40 for biasing the blade disposed on another side of the supporting member, and a link extending through said opening for joining the blade to said means.

5. A switch comprising a supporting member having an opening therein, a pivoted blade member supported on one side of the supporting member, resilient means for biasing the blade disposed on another side of the supporting member, and a link extending through said opening for joining the blade to said means, said supporting member constituting a fulcrum for the link. 45 50

6. A switch comprising a pivoted contact member provided with a member extending beyond its point of pivotal support, a lever pivoted to the extending member and normally angularly disposed with respect thereto, means for exerting tension on the lever, and a fixed guide member for limiting the 60 degree of angularity between the lever and the said extending member. 65

7. A switch comprising a pivoted contact member provided with a member extending beyond its point of pivotal support, a lever pivoted to the extending member and normally angularly disposed with respect thereto, means for constantly exerting tension on the lever, and a fixed guide member on which the lever is slidable upon a change in 70 the degree of angularity between the lever and the said extension. 75

8. A switch comprising a supporting member, a pivoted blade member supported on one side thereof, resilient means for biasing the blade disposed on another side of the supporting member, a link for joining the blade to said means, and means engaging the link at successive points intermediate its ends for directing the movement thereof. 80

In testimony whereof, I have hereunto subscribed my name this 5th day of November, 1919.

FRANK F. FORSHEE.
